Patented July 6, 1915.

Fig. 2.

UNITED STATES PATENT OFFICE.

CHARLES FRANCIS SMITH AND JOHN ROBERTSON, OF DUTCHESS JUNCTION, NEW YORK.

CHAIN-CLAMP.

1,145,812.

Specification of Letters Patent.

Patented July 6, 1915.

Application filed January 27, 1915. Serial No. 4,688.

To all whom it may concern:

Be it known that we, CHARLES FRANCIS SMITH, a citizen of the United States, and JOHN ROBERTSON, a subject of the King of Great Britain, and both residents of Dutchess Junction, in the county of Dutchess and State of New York, have invented a new and Improved Chain-Clamp, of which the following is a full, clear, and 10 exact description.

This invention relates to hand operated implements, and has particular reference to a lever operated device for drawing together parts of a chain for connecting them or for 15 operating upon wires, cables or other parts which are to be drawn toward each other forcibly.

Among the objects of this invention is to simplify and generally improve the class of 20 devices described and claimed in our previous Patent, No. 1,051,771.

Among the principal improvements included in this invention, distinguishing it favorably from the previous device, is the 25 provision of means for throwing the locking pawl out of engaging position and so maintaining it during the extension of the device.

Another specific improvement relates to a pivoted shoe or means associated with the 30 main lever serving to prevent the locking or dragging action between it and the rack bar which is intended to be slipped bodily through or along said lever when the device is being extended preliminary to the forcible 35 operation of the device.

The foregoing and other objects of the invention will hereinafter be more fully described and claimed and illustrated in the drawings forming a part of this specification 40 in which like characters of reference indicate corresponding parts in all the views, and in which—

Figure 1 is a perspective view showing the application of the implement to separated 45 ends of a chain and indicating the manner of use thereof for the purpose of drawing said chain ends together; Fig. 2 is a vertical longitudinal section of the operating lever and parts associated therewith, and indicating in full and dotted lines the change 50 in position of such parts; Fig. 3 is a partial side elevation of the end of the clamp remote from the lever, certain parts being in section on the line 3—3 of Fig. 4; and Fig. 55 4 is a plan view of the parts shown in Fig. 3.

The several parts of the device may be made of any suitable materials, and the relative sizes and proportions, as well as the general design of the mechanism, may be varied to a considerable extent without departing 60 from the spirit of the invention hereinafter more fully set forth and specifically claimed.

Referring more particularly to the drawings we show a pair of substantially parallel straight bars 10 and 11. These bars lie comparatively close to each other in the same plane and are adapted to be reciprocated in said plane one over the other longitudinally in either direction, or, in other words, these bars are adapted to be given step-by-step 70 reciprocation in alternation one with respect to the other. As in the previous patent, each of the bars is provided at its free end with a downwardly and inwardly projecting hook which is typical of any suitable means for 75 attaching a device to be manipulated by the implement.

The main lever 12 is provided with a fork 13 which loosely straddles the bar 11 and is pivotally connected at 14 to the inner end 80 of the bar 10. The fork 13, therefore, constitutes a guide for the free end of the bar 11 during its reciprocations with relation to the bar 10.

At 15 we show a clevis of substantially 85 U-shape in cross section, the same being connected by rivets or the like 16 adjacent the inner end of the bar 11 and embracing the bar 10. The clevis, therefore, constitutes a guide controlling the sliding or reciprocating movements of the bar 10 with relation to the other bar. Either of the bars may be provided with a pin or other stop means adapted to coöperate with the guide connected to the other bar for the purpose of 90 limiting the outward extension of the two bars. For this purpose we show a pin 17 extending into or through the bar 11 which, at the maximum extension of the device, will impinge against the guide or fork 13. The 100 contracting or shortening action of the device will be limited positively by coöperation between the shoulder 18 of the bar 10 and the projection 19 of the other bar. No trouble or annoyance, therefore, can result 105 due to the carelessness in the operation of one bar longitudinally with respect to the other in either direction.

At 20 we provide a pawl pivoted at 21 to the actuating lever and having a tooth en- 110

gageable with any of the ratchet teeth 22 formed on the bar 11. This pawl 20 is actuated upon by means of a pair of coil springs 23 wound around the pivot 21, one end of each of said springs being connected to a pin 24 on the side of the fork 13 and the other end of each spring is connected to a pin 25 secured to the side of the pawl 20. The normal tendency of the springs 23 is to straighten the pawl 20 into alignment with the axis of the lever 12, and hence, when the lever is moved forwardly in the direction of the arrow on Fig. 1, the springs 23 will tend to throw it in the opposite direction, causing the pawl 20 to ride loosely over the teeth 22. This action of the springs will insure the prompt engagement between the pawl 20 and the teeth 22 when the lever 12 is moved in the positive or actuating direction. When, however, the lever 12 is thrown rearwardly to the maximum extent, as shown in the dotted and dash lines of Fig. 2, a pin 26 will lift the pawl out of the path of the teeth 22 leaving the bar 11 free to be moved freely along the guide or fork 13.

At 27 we show a novel form of shoe having a substantially flat lower surface and pivoted intermediate its ends on the pivot 21 aforesaid in the fork 13 and above the bar 11. The space between the shoe 27 and the rack bar 11 is sufficient under ordinary conditions to permit the desired operation of the implement, but when the lever 12 is thrown rearwardly to its maximum extent, said shoe will prevent any part of the lever 12 from catching or binding upon the bar 11 and thereby interfering with its free movement.

A locking pawl 29 is pivoted at 30 on the end of the bar 11 opposite the lever 12. This locking pawl extends inwardly toward the lever 12 and is adapted to coöperate during the operation of the implement with teeth 31 formed on the bar 10. This pawl, irrespective of the position of the implement or direction in which the lever 12 may be extended for operation, is forced toward the teeth 31 by means of a flat spring 32 connected in this instance at one end to the end of the bar 11 at the point 33 close to the pivot 30, the free end of the spring extending inwardly and acting upon the pawl, as shown best in Fig. 3. The point of the pawl 29 operates close to the clevis 15 above described, and we provide means carried by said clevis for locking the pawl 29 out of action or out of the path of the teeth 31, when desired. The means just referred to includes a finger 34 pivoted on a pivot 35 extending into one side of the clevis, and that portion of the finger opposite the pivot constitutes a yoke 36 with which coöperates a cam 37. The cam 37 is pivoted eccentrically on a pivot 38 and is adapted to be rotated around said pivot through an angle

of approximately 200 degrees. The cam 37 is substantially circular where it fits in the yoke 36 and hence the rotation of the cam causes the finger 34 to swing around its pivot 35 far enough in one direction to lift the pawl 29 out of action, and the cam moves far enough in this connection for its crest to pass the dead center, as shown in dotted lines in Fig. 3, and thereby positively lock the finger 34 in position to hold the pawl 29 out of action against the tension of its spring 32. The cam 37 is rotated by a finger piece 39, and a spring 40 acting between the head of the pivot 38 and the cam 37 serves to prevent rattling or too free movement thereof.

With the chains or other parts to be drawn toward each other connected in any suitable manner to the hooks at the outer ends of the bars 10 and 11, and with the parts in the positions shown in Fig. 1, an oscillatory movement given to the lever 12, the forward direction will cause the hooks to approach each other, the bar 11 moving longitudinally over the other relatively due to the engagement of the pawl 29 with a tooth 22 and causing the pawl 29 to ride loosely over the teeth 31. While the lever 12 is oscillated in the opposite direction, the pawl 29 is effective to hold the parts in the position to which they have been previously brought and permitting a succeeding oscillation of the lever 12 to again advance the hooks toward each other. When it is desired to separate the hooks or to set the racks free for independent reciprocation, the operator will turn the cam in a clockwise direction, as viewed in Fig. 3, causing the finger 34 to be swung upwardly, lifting the pawl 29 and holding it out of action as above described. The cam will remain in this position, holding the finger in locking position until reversely rotated. When the pawl 29 is held out of action and the lever 12 drawn backward, the bar 11 may be pushed freely through the guide 13, causing one hook to be separated as far as desired from the other. By means of the devices herein set forth, the implement is adapted practically for a one hand operation, being much more convenient for its several functions than devices heretofore proposed.

Having thus described our invention, we claim as new and desire to secure by Letters Patent:—

1. In a device of the character set forth, the combination with a pair of toothed bars adapted to reciprocate longitudinally one along the other, a pair of pawls coöperating with the two bars, and a lever serving to actuate said bars to cause them to move toward each other along parallel lines, of a guide secured to one of the bars and surrounding the other bar adjacent one of the pawls, a finger pivoted to the guide, and a rotary de-

vice pivoted to the guide and serving to cause the rotation of the finger for lifting the adjacent pawl out of action.

2. The combination of a pair of bars movable relatively to each other in parallel lines, a lever and pawl to cause such movement, a locking pawl pivoted to one bar and coöperating with teeth on the other bar serving to hold the bars in the position to which they may be forced by the action of the lever and pawl, means tending to hold the locking pawl in locking position, a finger, and a rotary cam co-acting with the finger and serving to cause the finger to lift the pawl and hold it out of locking position.

3. The combination of two relatively movable parallel members, one of said members having teeth, a pawl pivoted to the member opposite the teeth and coöperating with said teeth, a clevis secured to one of said members and extending thence around the other forming a guide, a finger pivoted to said clevis adjacent the pawl, the end of the finger remote from the pawl constituting a yoke, a rotary member fitted in said yoke and pivoted eccentrically to the clevis, and means to rotate the cam, causing the finger to lift and hold the pawl out of coöperation with said teeth.

4. In a device of the character set forth, the combination of a reciprocating member, a pawl pivoted thereto, a toothed bar parallel to said reciprocating member, said pawl coöperating with the teeth of said bar, a clevis connected to the member having the pawl and surrounding the bar constituting a guide therefor, a spring anchored to the member adjacent the pivot of the pawl and acting normally upon the pawl, forcing it into coöperation with the bar, a finger pivoted to the clevis adjacent the pawl, and

means coöperating with the finger to swing it on its pivot and lock it in position to hold the pawl out of action against the tension of its spring.

5. In a device of the character set forth, the combination of a pair of parallel toothed bars, a lever having a fork spanning one of the bars and pivoted to the other bar, a pawl pivoted to the lever adjacent the fork, a spring acting upon the pawl forcing it toward the bar spanned by the fork, and a pin carried by the fork and serving to lift the pawl away from the bar when the lever is thrown in one direction.

6. In a device of the character set forth, the combination of two parallel relatively movable bars, each having ratchet teeth, an actuating lever having a fork spanning one of the bars and pivoted to the other bar, said fork constituting a guide for the spanned bar, means extending between the two bars at their ends remote from the lever serving to control their relative movements, a pawl connected to the lever and coöperating directly with one of said bars to move it along the other bar, and a shoe pivoted within the fork and slightly spaced from the teeth of the bar guided therein, said shoe coöperating with the bar, however, when the lever is thrown to maximum extent serving to prevent interlocking between the lever and the bar.

In testimony whereof we have signed our names to this specification in the presence of two subscribing witnesses.
